UNITED STATES PATENT OFFICE.

GEORGE H. MILLEN, OF HULL, QUEBEC, CANADA, ASSIGNOR TO THE
DIAMOND MATCH COMPANY, OF WILMINGTON, DELAWARE.

MACHINE FOR TRANSFERRING MATCHES FROM THE DIPPING-FRAME, &c.

SPECIFICATION forming part of Letters Patent No. 281,776, dated July 24, 1883.

Application filed January 3, 1883. (No model.)

To all whom it may concern:

Be it known that I, GEORGE HENRY MILLEN, of the city of Hull, county of Ottawa, Province of Quebec, and Dominion of Canada, have 5 invented new and useful Improvements in Machines for Transferring Matches from the Dipping-Frame to Proper Receptacles; and I do hereby declare that the following is a full and exact description of the same, reference being 10 had to the accompanying drawings, and to the letters of reference marked thereon.

This invention consists, mainly, in the combination of mechanism for imparting a continuous movement to a traveling belt, with 15 mechanism for discharging the matches upon the belt, the construction being such that by means of this belt the matches discharged from the dipping-frame thereupon are transferred, without hand manipulation, to receptacles de- 20 signed to receive them, as will be fully described hereinafter.

In the drawings, Figure 1 is a perspective view, representing the entire machine and illustrating its operation. Fig. 2 is a plan 25 view of the dipping-frame. Fig. 3 is a perspective view of the same, partially broken away to show the actuating-cam; and Fig. 4, a transverse vertical sectional view of the same.

To enable others skilled in the art to make 30 my invention and properly use the same, I will proceed to describe fully its construction and manner of operation.

A represents a frame-work of any proper construction, which is provided with the bearings a for the main shaft, the bearings a' for 35 the auxiliary shaft, and the vertical standard a^2 , having the transverse cross-bar or beam a^3 , as shown.

B represents the main shaft, adapted to receive motion from any proper source of power, 40 which is provided with the large roller b , as shown.

C represents the auxiliary shaft, having the small roller c , as shown.

D represents an endless belt or apron, which 45 passes about the rollers b c in the manner well understood, its upper surface lying in an inclined plane, as shown.

E represents a dipping-frame consisting of 50 three parallel plates of suitable form and size,

the two outer ones of which are rigidly united together, with an intervening space, by means of bolts and washers, or other proper means, and the inner one of which, although held against displacement by the bolts, is free to 55 move relatively to the other two, this action being permitted by slots e e , as shown.

F represents a cam, by means of which the inner plate is moved independently of the others, to clamp the matches or release the 60 same when desired.

G represents any proper receptacle, which is held at the lower end of the belt in an inclined position, as shown.

The dipping-frame E, when in position upon 65 the machine, lies upon the cross-bars a^3 of the standards a^2 a sufficient distance above the belt to allow all the matches to clear the frame in falling when they are released.

The operation is substantially as follows: 70 A dipping-frame filled with matches having been placed upon the cross-bars of the vertical standard a^2 , and movement having been communicated to the belt, the cam F may be actuated to release the matches from the frame. 75 All the matches in the frame having been released by a single movement, they fall together upon the belt, and together move downward, head foremost, to the receptacle at the lower end of the machine, each match, however, being separated from its fellow by a distance equaling the distance between the perforations in the dipping-frame. As each row of matches arrives at the discharge end of the belt it is turned off from the same into the receptacle 80 G, in the manner well understood.

The receptacle may be advanced either automatically or by hand as the matches accumulate, for the purpose of receiving the matches 85 properly as they come.

The machine, of course, is kept supplied 90 with frames, and also with receptacles, as the circumstances require.

The dipping-frame E, having been made the subject of another application, is not specifically claimed in this.

Having thus fully described my invention, what I claim as new, and desire to secure by Letters Patent, is—

1. A dipping-frame, substantially as de- 100

scribed, adapted to simultaneously discharge its contents, in combination with mechanism, substantially as described, having proper supports for holding the dipping-frame, and an 5 endless belt for conveying the discharged matches to a proper receptacle.

2. The machine described, having the frame A, with standards a^2 a^2 , adapted for support-

ing the dipping-frame, rollers b c , endless belt D, and receptacle G, as described.

This specification signed and witnessed this 29th day of December, 1882.

GEO. H. MILLEN.
